His Attorney.

UNITED STATES PATENT OFFICE

JETSON O. BENTLEY, OF BEACON, NEW YORK, ASSIGNOR TO GENERAL ELECTRIC COMPANY, A CORPORATION OF NEW YORK

TRANSMISSION OF PICTURES

Application filed August 16, 1929. Serial No. 386,270.

My invention relates to the transmission of pictures, and has for its principal object the provision of an improved picture transmitting apparatus and method of operation whereby a picture of good quality is produced by means of a relatively limited range of modulation frequencies.

In the transmission of pictures it is customary to scan the picture along successive vertical lines, horizontal lines, or spirally shaped lines. These methods of scanning are satisfactory where the lines per inch can be made high enough to give fine details. It sometimes happens, however, that the apparatus must be operated within a limited range of frequencies. Under these conditions the picture is likely to be unsatisfactory for the reason that its details are too coarse. In accordance with my invention this difficulty is avoided by scanning the picture radially, so that the details of the picture produced vary in fineness from the center to the perimeter.

If the number of lines per inch be considered as the mesh of the picture, a picture, produced in this way would have a coarse mesh at the border and a finer mesh at the center. The details will thus be exceptionally good near the center. Thus assuming a circular picture which has a radius R and is scanned vertically with S lines per inch and a similar picture scanned radially, using the same total number of lines for the two pictures, it is found that the mesh of the radially scanned picture will be about the same as that from the vertically scanned picture on the circumference of a circle whose radius is $.637 R$ (R being the radius of the picture). To the eye it will appear that approximately $\frac{2}{3}$ of the picture is equal to or better in mesh than the vertically scanned picture. Actually 40.6% of the picture will be equal to or better in mesh than the vertically scanned picture. There is thus produced a marked improvement in the central portion of the picture at a sacrifice of detail near the circumference. This lack of detail near the circumference appears as a loss of light intensity. This defect may be counteracted as hereinafter explained by increasing the

width of the scanning beam as this beam approaches the edge of the picture.

My invention will be better understood from the following description when considered in connection with the accompanying drawing and its scope will be pointed out in the appended claims.

The single figure of the drawing is a diagrammatic illustration of a picture transmitting apparatus wherein my invention has been embodied.

This apparatus includes a picture 10 upon which light is projected from a source 11 through a lens 12, a fixed gear 13, a rotatable disc 14, a slotted rotatable member 16 and a lens 17. The light reflected from the successive elemental areas of the picture or image is received by a plurality of light sensitive cells 18 through which it is converted into electrical impulses corresponding to the shade of these elemental areas. These impulses are utilized in a well known manner to control the output of the radio transmitter 19.

The member 16 is closed at one end except for a slot 20, is in the form of a hollow cylinder, is mounted in bearings 21 and 22 and is arranged to be rotated by suitable means such as a motor 23 to which it is geared through gears 24 and 25. At its closed end the member 16 is provided with a bearing 26 in which the shaft of the disc 14 is journaled. At the opposite end of this shaft a gear 27 is provided. Diametrically opposite the bearing 26 is provided a counterweight 28 for counterbalancing the weight of the bearing 26 and disc 14.

The operation of the apparatus will be readily understood without detailed explanation. As the member 16 rotates in the bearings 21 and 22 the shaft of the disc 14 is revolved and rotation of this disc is produced due to the gear 27 which meshes with the stationary gear 13. The relation between the rotational speed of the member 16 and the disc 14 is of course dependent on the gearing ratio. The member 16 rotates at a much slower speed than the disc 14 which is provided with a plurality of radial slots 29. The light projected on the picture bearing

screen 10 from the light source 11 is dependent on the space relation between the slot 20 of the member 16 and the slots 29 of the disc 14. As each slot sweeps past the slot 20 a radial line is traced on the picture bearing member.

If the cylindrical member 16 is rotated at a speed of twenty-one revolutions per second and the ratio of gear 27 and gear 13 is 10 2:1, then the disc 14 will rotate at forty-two revolutions per second. Under these conditions the twelve slots in the disc 14 will sweep across the slot 20 twice for every revolution of the cylinder member 16. This will correspond to a twenty-four line picture and twenty-one pictures per second. As will be readily understood by those skilled in the art, any other desired combination of pictures per second and lines per picture may be 20 readily secured.

It will be observed that the slot 20 in the cylindrical member 16 is comparatively narrow at its center and comparatively wide at its ends. By thus increasing the width of 25 the slot from its center outwardly, the illumination near the edges of the picture is made substantially the same as at the center. The detail of the picture of course is not improved by making the illumination uniform 30 throughout the picture, but the lack of detail near the edge of the picture is not likely to be objectionable where the picture is of good quality in its central area.

The embodiment of the invention illustrated and described herein has been selected 35 for the purpose of clearly setting forth the principles involved. It will be apparent, however, that the invention is susceptible of being modified to meet the different conditions encountered in its use and I therefore aim to cover by the appended claims all 40 modifications within the true spirit and scope of my invention.

What I claim as new and desire to secure 45 by Letters Patent of the United States, is:

1. The method of picture transmission which comprises successively scanning a picture along radial lines, and increasing the size of the scanning beam near the ends of 50 said lines.

2. A picture transmitting apparatus comprising a slotted member rotatable on an axis passing through the slot intermediate its ends, and a rotatable disc provided with a 55 plurality of radial slots arranged to be successively moved past the slot in said rotatable member.

3. A picture transmitting apparatus including a rotatable cylindrical member closed 60 at one of its ends and provided with a slot in said end, a bearing mounted on said rotatable member, a rotatable disc provided with a plurality of radial slots and with a shaft mounted in said bearing, and means for causing 65 the slots in said disc to be successively

swept past the slot of said cylindrical member.

4. A picture transmitting apparatus including a rotatable cylindrical member closed at one of its ends and provided with a slot 70 in said end, a bearing mounted on said rotatable member, a rotatable disc provided with a plurality of radial slots and with a shaft mounted in said bearing, a stationary gear and a gear mounted on said shaft and arranged to cooperate with said stationary gear for causing the slots of said disc to be moved successively past the slots of said cylindrical member. 75

5. A picture transmitting apparatus including a rotatable cylindrical member closed at one of its ends and provided with a slot 80 in said end, a bearing mounted on said rotatable member, a rotatable disc provided with a plurality of radial slots and with a shaft mounted in said bearing, a stationary gear and a gear mounted on said shaft and arranged to cooperate with said stationary gear for causing the slots of said disc to be moved successively past the slots of said cylindrical member, and driving means geared to said cylindrical member. 85

6. A picture transmitting apparatus comprising a rotatable member having a slot 90 therein intersecting the axis of rotation, a rotatable disk having radial slots arranged to be moved past the slot in the rotatable member, means for revolving the axis of rotation of the disk with said rotatable member and means for rotating said member and disk. 95

7. A picture transmitting apparatus comprising a rotatable member having a slot 100 therein extending through and on opposite sides of the axis of rotation, the ends of the slot being wider than the intermediate portion, and a rotatable disk provided with a plurality of radial slots arranged to be successively moved past the slot in the rotatable member. 105

In witness whereof I have hereunto set my 110 hand this 2d day of August, 1929.

JETSON O. BENTLEY.
